US00D900599S

(12) **United States Design Patent** (10) Patent No.: **US D900,599 S**
(45) Date of Patent: **** Nov. 3, 2020**

(54)	HOOK FOR A ROD FOR USE WITH HANGING FILE HOLDERS	1,348,546 A	8/1920	Cutler
(71)	Applicant: LSC COMMUNICATIONS US, LLC, Chicago, IL (US)	1,524,348 A	1/1925	Field
(72)	Inventors: Andrew Goodfellow , Phoenix, AZ (US); David Gruza , Phoenix, AZ (US); Christopher Holman , Mesa, AZ (US); Candie Harris , Brookville, NY (US); Braden Jones , Phoenix, AZ (US)	1,867,158 A	7/1932	Kline
(73)	Assignee: LSC Communications US, LLC, Chicago, IL (US)	1,867,159 A	7/1932	Kline
(**)	Term: 15 Years	1,953,552 A	4/1934	Dequeker
(21)	Appl. No.: 29/725,608	2,257,052 A	9/1941	Hanna
(22)	Filed: Feb. 26, 2020	2,325,317 A	7/1943	Hanna
	Related U.S. Application Data	2,519,996 A	8/1950	Blake
(63)	Continuation of application No. 16/785,178, filed on Feb. 7, 2020, which is a continuation of application No. 15/800,487, filed on Nov. 1, 2017, which is a continuation of application No. 15/407,688, filed on Jan. 17, 2017, now Pat. No. 9,809,048, which is a continuation of application No. 11/877,045, filed on Oct. 23, 2007, now Pat. No. 9,573,408.	2,524,743 A	10/1950	Wright
(51)	LOC (12) Cl. 08-05	2,605,769 A	8/1952	Lampel
(52)	U.S. Cl. D8/367	2,608,420 A	8/1952	Eck
(58)	Field of Classification Search USPC .... D8/367, 354, 349, 356; D12/162; 47/46; D6/315; D19/32, 211/45 CPC ... A47G 29/083; F16B 45/00; A63B 21/0557; B60P 7/0823; E01F 16/06; B42F 15/0035 See application file for complete search history.	2,626,610 A	1/1953	McTavish et al.

CLAIM

The ornamental design for "a hook for a rod for use with hanging file holders," as shown and described.

DESCRIPTION

FIG. 1 is a front, left, perspective view of a hook for a rod for use with hanging file holders.

FIG. 2 is a front view of the hook of FIG. 1.

FIG. 3 is a top view of the hook of FIG. 1.

FIG. 4 is a left side view of the hook of FIG. 1; and, FIG. 5 is a front, left, perspective view of the hook of FIG. 1 showing a portion of a hanging file holder for environment.

The rear, bottom, and right views do not form part of the claimed design.

The features shown in broken lines form no part of the claimed design.

1 Claim, 3 Drawing Sheets
